W. H. CONIBEAR

SLIDING LEG ELLIPSOGRAPH

Filed July 21, 1925

William H. Conibear,

INVENTOR

BY Victor J. Evans

ATTORNEY

P. J. Hickey.

WITNESS:

UNITED STATES PATENT OFFICE.

WILLIAM H. CONIBEAR, OF SILVERTON, OREGON.

SLIDING-LEG ELLIPSOGRAPH.

Application filed July 21, 1925. Serial No. 45,066.

The object of this invention is to provide means for striking an ellipse, the device to include a segmental element provided with graduations, and a slidable element movable on said segmental element, this slidable element being formed with a main leg, and serving to slidably mount a sleeve on which is pivoted a second leg movable with reference to the leg first named and adapted to be secured in an adjusted position.

To the attainment of the foregoing, the invention consists in the improvement as hereinafter described and definitely claimed.

In the drawing forming part of this application—

The figure shows the device in perspective and in operative position.

A segmental element 10 is graduated and forms a part of a true circle, the graduations employed running from 20 degrees to 90 degrees. The lower end is deflected as shown to form a leg portion 11, and other leg portions 12 and 13 have the relation to element 11 illustrated in the drawing.

A clamp or the like designated 15 includes a recessed portion open at one side, and the clamp is slidable along the segmental bar 10 and is adapted to be secured in an adjusted position by means of a screw 16.

Formed with clamp 15 is a main leg 17 having a lower end 18 to be placed on the center about which the ellipse is to be drawn. A sleeve 20 is slidable on leg 17 and includes ears 21 in which a short leg 22 is mounted by means of a pivot 23. Leg 22 has a slot 24 therein, and arm 25 formed

on sleeve 20 passes thru slot 24, the arm being curved as shown, and the pivoted leg 22 is secured in an adjusted position on arm 25 by means of screw 26.

The operation of the device in striking the ellipse will be understood by those skilled in the art.

Having thus described my invention, I claim:

1. A device of the class described, comprising an arcuate arm including leg portions and comprising a three-point mounting device for engagement with a flat surface, a clamp movable along said arm, means for retaining the clamp in an adjusted position on the arm, a main leg formed rigid with the clamp and extending inwardly forming the radius of a circle of which the arm forms an arc, a sleeve slidable on the main leg, and a scribing leg pivoted on the sleeve.

2. A device of the class described, comprising 90 degree arcuate arm provided with graduations, a main leg projecting inwardly from said segmental arm to form the radius of a circle of which the segmental bar forms an arc, a sleeve slidable on the main leg, a second leg pivotally mounted on the sleeve, an arm connected with the sleeve, and curved on the arc of a circle struck from the pivotal point of the second leg, guiding means formed on the second leg for cooperation with the arm on the sleeve, and means for retaining the second leg in an adjusted position with reference to the arm last named.

In testimony whereof I affix my signature.

WILLIAM H. CONIBEAR.
